Primary Examiner — Cynthia Ramirez*Assistant Examiner* — Xavier Marti-Santos(74) Attorney, Agent, or Firm — Bayramoglu Law Offices LLC(57) CLAIM

The ornamental design for a couch, as shown and described.

DESCRIPTION

FIG. 1 is a front perspective view of a couch showing our new design;

FIG. 2 is a front view thereof;

FIG. 3 is a rear view thereof;

FIG. 4 is a top view thereof;

FIG. 5 is a left side view thereof, the right side view being a mirror image thereof;

FIG. 6 is a rear perspective view thereof;

FIG. 7 is a perspective view in an alternate configuration; and,

FIG. 8 is a front view thereof.

The broken lines depict portions of the couch in which the design is embodied that form no part of the claimed design.

1 Claim, 8 Drawing Sheets(56)
